[57] CLAIM

The ornamental design for automobile combined stereo receiver and cassette tape player, as shown and described.

DESCRIPTION

FIG. 1 is front elevational view of an automobile combined stereo receiver and cassette tape player showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top and right side perspective view thereof;

FIG. 8 is a front and top perspective view thereof with the front cover pivoted open;

FIG. 9 is a top plan view thereof as shown in FIG. 8;

FIG. 10 is a front elevational view thereof as shown in FIG. 8;

FIG. 11 is a right side elevational view thereof as shown in FIG. 8; and

FIG. 12 is a view like FIG. 1 showing a digital display.
